UNITED STATES PATENT OFFICE.

JOSEPH H. ULLMAN, OF NEW HAVEN, CONNECTICUT, ASSIGNOR, BY MESNE ASSIGNMENTS, TO THE KING MACHINE COMPANY, OF BRIDGEPORT, CONNECTICUT, A CORPORATION OF CONNECTICUT.

IRONING-MACHINE

1,083,038.

Specification of Letters Patent. Patented Dec. 30, 1913.

Application filed June 5, 1913. Serial No. 771,903.

To all whom it may concern:

Be it known that I, JOSEPH H. ULLMAN, a citizen of the United States, residing at New Haven, in the county of New Haven and State of Connecticut, have invented certain new and useful Improvements in Ironing-Machines, of which the following is a specification.

My present invention pertains to ironing machines, the construction and advantages of which will be hereinafter set forth, reference being had to the annexed drawings, wherein:

Figure 1 is a sectional elevation of the machine, the parts being in a position of rest and the iron fully elevated at what may be termed the rear of the inward stroke; Fig. 2 a vertical sectional view, taken on the line 2—2 of Fig. 6, the parts being in operative position and the iron making its outward or forward stroke; Fig. 3 a sectional elevation of the upper portion of the machine, the full-line position showing the iron as having finished its outward stroke and raised from the board or support, and the dotted-line position the same relation or position at the end of the inward stroke; Fig. 4 a detail sectional view of the clutch mechanism, taken on the line 4—4 of Fig. 1, the parts being slightly enlarged; Fig. 5 a detail perspective view of the rocker which elevates the iron-carrying bar or rod; Fig. 6 a transverse vertical sectional view on the line 6—6 of Fig. 1; and Figs. 7 and 8 side and plan views, respectively, of the clutch-releasing and stop arm.

The main object of the present invention is to produce an ironing machine, adapted more especially for the ironing of corsets and the like, in which the iron will be elevated from the goods at the end of each forward and rearward stroke whereby the operator may readily shift the goods upon the table or support while the iron is so elevated.

A further object of the invention is to provide a mechanism which, when the operation of the machine is to be stopped, will bring the iron to rest in its fully elevated position and, preferably, when it is at the end of its inward or rearward stroke.

In the drawings, 1 denotes a suitable stand

or bench upon which is mounted an ironing-board or table 2, with which the iron 3 is adapted to coact. The iron is preferably electrically heated and is connected to an actuating bar or rod 4 through a yoke 5, pivotally connected to the outer end of the bar, the yoke in turn being likewise connected to the iron, through the agency of a pivot-pin 6. Said bar, as will be best seen upon reference to Fig. 6, passes between and is guided by the upright members 7 and 8 of a standard or frame 9, extending upwardly from a base plate or casting 10, secured to the stand or bench 1. The rear end of bar 4 is pivotally connected to the upper end of a lever 11 which latter is fulcrumed upon a shaft 12 which finds its support in gear-supporting frame or housing 13, secured upon the floor beneath the bench 1. Extending through said housing is a drive shaft 14, having secured thereto a fixed clutch member 15, adapted to coact with a sliding clutch member 16, formed integrally with or attached to a pinion 17. The sliding clutch member may be thrown into and out of locking engagement with member 15 through the agency of shifter 18 which is actuated through the agency of a lever 19. Normally this clutch will remain in locked position, as I employ a separate clutch to bring the iron to rest in its elevated position. Pinion 17, is in constant mesh with a gear 20 secured to shaft 21, which likewise has keyed to it a pinion 22, Fig. 1, said pinion meshing with a gear 23 secured upon a shaft 24. Said shaft projects outwardly beyond the housing or frame 13, see Figs. 4 and 6, and carries a clutch member 25, said member in the form shown being formed integrally with the shaft. A series of openings 26 is formed in said member, said openings being adapted to coact with a locking pin or bolt 27, mounted in a recess formed in a crank-disk 28. A spring 29, mounted interiorly of the pin and bearing at its outer end against a screw plug 30, secured in the crank-disk, urges the bolt into locking engagement with the clutch member or perforate disk 25. Bolt 27 is formed with a laterally-extending lug or finger 31 which is cut away and beveled as at 32, Fig. 7, to permit the retracting member,

shortly to be described, to properly function therewith. A pitman 33 is connected to the disk 28, and likewise to lever 11, and serves to rock said lever back and forth upon shaft 12.

- 5 A treadle 34 is fulcrumed upon a stand 35 secured to the floor, the inner end of the treadle being normally depressed as by a spring 36. A link 37 is pivotally connected 10 to the inner end of the treadle and at its upper end is likewise connected to the outer end of a clutch-releasing and stop arm or lever 38. Said lever is fulcrumed on a rod 38^a, Fig. 2, and the free end thereof stands 15 in line with lug 31 of the bolt 27, said end being curved, see Fig. 7, and formed with a beveled or inclined face 39, which terminates adjacent a stop lug 40.

When the machine is at rest, lug 31 contacts with lug 40, the beveled end 32 having passed into contact with the inclined face 39 and withdrawn the bolt 27, the parts then being in the position shown in Fig. 4, the crank-disk being at rest and held against 25 any movement owing to friction of the shaft 24 and disk 25, which still continue to rotate. This disengagement takes place when the operator removes his foot from the treadle.

- 30 Pivotally connected to lever 38 and extending upwardly therefrom is a link 41, said link having a slot 42 formed in the upper end thereof and into which extends a pin or screw projecting outwardly from an 35 arm or lever 43 secured to the protruding end of a shaft 44 journaled in the uprights 7 and 8. A V-shaped rocker, having a relatively short arm 45 and a long arm 46 is secured to said shaft, and a spring 47 tends to 40 move the shaft clockwise and to thereby bring the short arm to a substantially vertical position, Fig. 2.

Extending downwardly from bar 4, adjacent its inner end, is a lug or bracket 48, 45 a second bracket having a short arm 49 and a longer arm 50, being likewise secured to the bar adjacent its outer end and the iron carried thereby. These brackets coacting with the rocker serve to elevate the bar 4, 50 and consequently the iron, in the following manner: When the operator depresses the treadle, as in Fig. 2, the clutch lever 38 is withdrawn from engagement with bolt 27, the parts moving from the position shown 55 in Figs. 1 and 6 (where they are at rest) to the position illustrated in Fig. 2. When the bolt passes into one of the openings 26, crank disk 28 is locked to shaft 24 and rotated therewith; consequently, lever 11 will 60 be drawn forward and bar 4 pushed outwardly. As bar 4 moves forwardly, the rocker also swings forwardly, arm 46 moving downwardly with the bar, and the iron coming to rest upon the goods or article 65 upon the table 2. The parts are then in the

positions shown in Fig. 2, the short arm 45 of the rocker swinging up to substantially a vertical position and in the path of bracket 48. As bar 4 nears the limit of its outward movement, said bracket contacts with the 70 arm 45, said arm then acting as a fulcrum, see full line position, Fig. 3, and causing the outer end of the bar to be elevated and the iron to be raised or lifted clear of the board. Upon the return movement of the bar, the rocker is drawn or swung rearwardly by contact with the bar, and ceases to hold the same elevated, the iron being lowered and resting on the board during its return or inward movement. 75

The parts are so proportioned that during the movements thereof and while the iron is upon the board the pin upon lever or crank 43 does not contact with the upper 80 end wall of slot 42, spring 47 at such time serving to turn the rocker forwardly and bring arm 45 into contact with the under face of the bar 4, see Fig. 2. When the parts are in this position, and the iron-carrying bar 4 is moving inwardly the forward 85 end of arm 46 of the rocker will lie in a plane below arm 49 and clear the same, finally coming into contact with the longer arm 50 and being rocked rearwardly thereby. This causes the arm 50 to lift the iron-carrying bar as said bar reaches its limit of 90 inward motion. Upon a reversal of the direction of movement of bar 4, the rocker will swing forwardly, thereby lowering the bar and the iron, the latter traveling over the board until it reaches its limit of outward movement, when it will be again elevated. This cycle of operations continues 95 until the operator releases the treadle. When this is done, the clutch-releasing lever moves up into the path of the bolt 27, and withdrawing it releases crank disk 28 from the driving shaft 24. At the same 100 time, link 41 is drawn down and the end thereof engaging the pin on lever 43, holds the rocker against forward movement in opposition to spring 47, thereby holding arm 46 in the path of the short arm or projection 49 of the forward bracket. Shortly after these arms contact, which they do just 105 before the clutch connection is broken, bar 4 will be elevated to its full extent, as shown in Fig. 1, the machine then coming to rest. By lifting the iron to a considerable extent when it reaches its limit of inward movement and comes to rest, the table is left substantially unobstructed, and a new cover or felt may be placed on the board without fear on the part of the operator of being 110 burned by the iron. 115

It is, of course, conceivable that the connection between the rocker and the clutch-withdrawing lever may be omitted, in which event the rocker would act only upon the brackets or projections 48 and 50, the for- 120 125 130 135

ward long arm of the rocker under such conditions being held by the rocker spring out of the path of member 49 at all times.

Having thus described my invention, what I claim is:

1. In an ironing machine, the combination of a table or support for the material to be ironed; an iron; a bar carrying said iron; means for moving said bar endwise; a pivoted rocker located beneath said bar; and means carried by the bar and coacting with the rocker to cause the bar, and consequently the iron, to be elevated at the end of each inward and outward stroke.
2. In an ironing machine, the combination of a table or support for the material to be ironed; an iron; a bar carrying said iron; means, including a releasable clutch, for imparting endwise movement to said bar; a pivoted rocker located beneath the bar; a projection extending downwardly from the bar adjacent that end remote from the iron and adapted to coact with one arm of the rocker to raise the bar; a pair of projections also extending downwardly from the bar adjacent the iron, the forward projection being longer than the other, said projections being adapted to coact with the forward arm of the rocker; a spring acting upon the rocker and tending to hold the rear arm thereof up toward the bar; a lever adapted to throw the clutch out of locking engagement; and connections between said lever and the rocker to hold the rocker against the action of the spring, and to thereby bring the forward arm thereof into the path of the short projection of the forward pair.
3. In an ironing machine, the combination of a table or support for the material to be ironed; an iron; a bar carrying said iron; means for imparting an endwise reciprocating movement to said bar and thereby causing the iron to traverse the table back and forth; means for elevating the bar, and consequently the iron, at the end of each forward and backward stroke; and means for elevating the bar, and consequently the iron, to a greater extent when the bar is brought to rest.
4. In an ironing machine, the combination of a table or support for the material to be ironed; an iron; a bar carrying said iron; means for imparting an endwise reciprocating movement to said bar and thereby causing the iron to traverse the table back and forth; a V-shaped rocker pivotally mounted below the bar; a projection extending downwardly from the bar adjacent its rear end; a pair of projections also extending downwardly from the bar adjacent its forward end, the forward projection being longer than the other; a spring tending to

tilt the rocker forwardly; and means for holding the rocker against the action of the spring when the bar actuating mechanism is brought to rest, whereby the forward end of the rocker will be held in the path of the short forward projection and the bar and iron carried to their extreme elevation.

5. In an ironing machine, the combination of a table or support for the material to be ironed; an iron; a bar carrying said iron; a lever fulcrumed at its lower end and pivotally connected at its upper end to the rear end of said bar; a constantly driven shaft; a clutch member carried thereby; a crank disk loosely mounted on said shaft; a pitman connecting said disk and the lever aforesaid; a spring-actuated clutch member carried by said disk and normally engaging said clutch member on the shaft; a combined clutch-releasing and stop lever adapted to withdraw the spring-actuated clutch member and to arrest the movement of the crank disk; a treadle connected to said lever; a spring for normally throwing said lever into clutch-releasing position; a V-shaped rocker pivotally mounted below the iron-carrying bar; a spring tending to tilt the rocker forwardly; a crank arm or lever connected to the rocker; a link having at its upper end a slotted connection with the crank, the lower end being connected to the combined clutch and stop lever aforesaid; a bracket or projection extending downwardly from the iron-carrying bar adjacent its rear end; and a second bracket secured to the bar adjacent its forward end, said second bracket being formed with two downwardly-extending projections, the forward one being longer than the other and adapted, when the machine is in normal operation, to contact with the rocker, while the shorter one comes into contact with the rocker as the bar is brought to rest and elevates the bar to its full extent.

6. In an ironing machine, the combination of a table adapted to support the material to be ironed; an iron; a bar to which said iron is connected; means for imparting an endwise reciprocating motion to said bar; a member extending downwardly from the bar adjacent each end thereof; and a rocker member lying below the bar and adapted to alternately engage said downwardly-extending members and to elevate the bar and consequently the iron.

In testimony whereof I have signed my name to this specification in the presence of two subscribing witnesses.

JOSEPH H. ULLMAN.
